[57] CLAIM

The ornamental design for a basketball return attachment, as shown and described.

DESCRIPTION

FIG. 1 is a perspective view of a basketball return attachment in a position when in use showing our new design;

FIG. 2 is a top plan view in its collapsed state thereof;

FIG. 3 is a side elevation view thereof;

FIG. 4 is a bottom plan view thereof;

FIG. 5 is a rear elevation view thereof; and,

FIG. 6 is a front elevation view thereof.

The broken lines are for illustrative purposes only and form no part of the claimed design.

FIG. 1

FIG. 2

FIG. 3

FIG. 4
